J. Boynton.
Carding Mach.

Patented Mar 11, 1833.

94774 John Mayerton March 11, 1833
Scotia Patent

The subscriber informed to in their Letters Patent and making part
of the same containing a description in the words of the said John
Mayerton himself of his improvement in the wool carding or
giving machine. To all to whom these presents shall come:
Be it known that of John Mayerton of ... County in
the County of Scotland and State of Connecticut have invented
a new and useful improvement in the wool carding
engine or machine and consisting in the application
of the same to the carding and drawing of cotton & flax and
that the following is a full and exact description of the con-
struction and operation of the said improvement ad-
ministered or improved and applied by me. The improvement
to which I claim an exclusive right is contained in that
part of the machine which makes the fine ropey fiber for
the spinning, pack or other spinning and it is supposed not
necessary to describe the whole machine which has for a long
time been in use. The tube spindle rails are made with
a flat bottom of wood or metal 3 or more inches wide &
a little larger than the cylinder of the machine with
upright side pieces between & through which the tube spindles
are inserted. Under these spindles is the belt or strap
which turns them by the friction of their own weight lay-
ing on the strap. This strap or belt is carried by a pulley
upon a shaft or arbor placed in a right angle with the
main shaft & driven by belt gear attached to the main
shaft. The tube rails containing the spindles are placed
one over the other each to correspond with a copper cylinder
over each shaft. The strap is removed from the top of the pulley
under the spindles in the upper tube and passing over a
pulley at the other end of the rail in an upright stand
of the same width above in the same stand

the tubes are set in the bottom tube and to the
bottom of the tube and the outer side of the pipe to receive
the metal. The filling tube is of such length to encircle an
amount of metal so as to form a trumpet nose to which
the rope is gathered & passing through the spindle being
driven by the small rollers at the outer end of the spindle goes
off to the spool on which it is wound fit for spinning. The
top side of the spindle may be made of equal diameter to
the width of the card being from which the rope is to be made.

The great advantage of the trumpet nose is that its cir-
cumference on the inside is much greater & creates more fric-
tion on the rope & gives it more twist as it comes from the card
& makes it stronger, more dense and more durable than any other
like nose in use by the sheep or belt spinning in this manner besides
all the tubes carries them all with equal velocity & dispenses
the necessity of a number of bands as has been the usual
mode. The improvement in the shape of the tube spindle
is considerable and the manner of driving them by laying them
all on a single belt or strap the tubes in the top spindle all
lying on the out side of the belt or strap & those in the bottom
spindle not lying on the inside of the belt or strap, said
belt or strap is of such width & that of all other parts of the in-
gine may be varied in size to accommodate the particular
kind of stock that is to be used & the going to be made of the suc-
cessful application of the same novel carding engine with the
tube or other contrivance to the carding and rope carding
bottom and strap, is all that I claim as particularly my own invention
improvement or discovery for application for which I claim reward
by patent
